FRANK A. PENBERTHY, OF CANTON, OHIO

SMOKE CONSUMER AND FUEL ECONOMIZER

Application filed January 26, 1927. Serial No. 163,591.

My invention relates to smoke consumers and fuel economizers more particularly for use in connection with boilers fired with solid fuels such as coal and the like.

5 A major difficulty in connection with the operation of such boilers has been an inability to positively and continuously control the combustion of the fuel under the boiler and in the firebox and combustion chamber, so that the fuel will continuously and economically burn with maximum combustion efficiency and minimum eduction of smoke from the chimney.

Not only from the standpoint of efficiency 15 and economy of boiler operation, but also from the social standpoint particularly in crowded communities, it is desirable to control the eduction of smoke from the chimneys of boiler furnaces, and in some localities laws 20 are in effect regulating the character of smoke which will be permitted to be given off by a chimney.

From the standpoint of combustion, it is well known that the fuel bed in the firebox 25 of a boiler furnace of the usual type, educes into the firebox a quantity of combustible gases and soot which are not completely burned in the firebox, nor under usual conditions in the furnace combustion chamber with 30 which the firebox usually communicates over a bridge wall.

These unburned combustible gases and the soot suspended therein form the objectionable smoke which issues in varying degrees 35 from the chimneys of boiler furnaces, and the like.

It is also well known that combustion of any sort requires, first, that the combustible matter be heated to its combustion temperature, and, second, that the combustible matter be provided with an adequate supply of oxygen to support combustion.

In the case of the combustible gases and 45 suspended soot usually educed from the fuel bed in the firebox of a boiler furnace, it is therefore necessary, first, to heat the mixture of combustible gases and suspended soot therein to the temperature necessary for the combustion thereof, and, second, to supply

the necessary quantity of oxygen for this combustion.

There is usually available in the firebox of a boiler furnace, a sufficient total quantity of oxygen, as a component of the air, to support the combustion of the gases and soot, but the ordinary movement of the gases and soot through the firebox over the bridge wall and through the combustion chamber is such that part of the same never comes in contact with 55 air, the air and the combustible gases and soot passing through the firebox and combustion chamber more or less in stratified 60 layers.

In order to completely burn the combustible gases and soot which will constitute smoke if they are not burned before issuing from the chimney, it is necessary that they be rapidly, thoroughly, and continuously 65 heated to their combustion temperature and rapidly, thoroughly, and continuously intimately mixed with the proper quantity of air, 70 preferably as soon after the combustible gases and soot arise from the fuel bed as possible.

The objects of the present invention are to provide an apparatus adaptable for use in connection with substantially any well known 75 type of boiler, and which will consume smoke and thereby economize fuel by automatically and continuously maintaining in the firebox and combustion chamber of the boiler furnace an intimate mixture of the aforesaid combustible gases and soot educed from the fuel bed with proper quantity of air and heated 80 to the necessary temperature to support combustion thereof.

These objects are attained by a construction and arrangement which may be stated in general terms as including, first, a whirler 85 nozzle directed over the fuel bed in the furnace firebox under the boiler or the like, and delivering whirling superheated steam into the firebox whereby the combustible gases and soot arising from the fuel bed are simultaneously whirled and mixed with the air normally flowing through the firebox by the operation of the boiler furnace draft device, and heated to the proper combustion temperature; 90 second, an apertured bridge wall between the 95

firebox and the combustion chamber, whereby any smoke which may still remain, is broken up in passing from the firebox to the combustion chamber; and, third, means for injecting superheated steam into the combustion chamber preferably immediately adjacent the bridge wall, whereby the broken up smoke which has passed from the firebox to the combustion chamber through the apertured bridge wall is agitated, mixed, and heated with the air normally passing through the combustion chamber, so that practically complete combustion of the smoke is obtained.

15 A preferred embodiment of the invention is illustrated in the accompanying drawings forming part hereof, in which:

Figure 1 is a longitudinal vertical cross section illustrating the improved smoke consumer and fuel economizer in connection with a fire tube boiler installation, as on line 1—1, 20 Fig. 2;

Fig. 2, a horizontal cross section thereof as on line 2—2, Fig. 1;

25 Fig. 3, a fragmentary detailed horizontal cross section of the improved whirler nozzle as on line 3—3, Figs. 1 and 2;

Fig. 4, an enlarged fragmentary cross sectional view similar to Fig. 1 of a preferred 30 form of superheater for the improved device; and

Fig. 5, an enlarged fragmentary top plan view of the superheater as on line 5—5, Fig. 4, illustrating the plurality of orifices in the 35 top pipe thereof for delivering superheated steam into the furnace combustion chamber.

Similar numerals refer to similar parts throughout the several views.

A boiler indicated generally at 1 as being 40 a fire tube boiler of any usual and well known design, is mounted upon a suitable setting indicated generally at 2, and which may include side walls 3 and 4, back wall 5, and front wall 6 made in accordance with usual 45 practice of suitable refractory material, and resting upon a suitable foundation 7, and the walls may furthermore support a suitable refractory arch cover 8 for the boiler.

A furnace enclosure is thus formed by the 50 walls rising from the foundation and provided with the arch cover, and this enclosure is divided by an improved bridge wall 9 properly spaced therein between the back wall 5 and the front wall 6, to form a firebox 55 10 and an improved combustion chamber 11 beneath the boiler.

Grate bars 12 may be supported in a usual manner upon suitable ledges secured at the opposite faces of the bridge wall and the 60 front wall, and forming a grate upon which the fuel bed 13 is carried, and through which ashes may drop to the ash pit 14 below the grate bars.

The front wall 6 of the setting may be 65 provided with one or more of the usual fir-

ing doors 15 and ash removing doors 16. Excepting for the improved bridge wall 9, the details of which will presently be described, the foregoing boiler and setting is typical of fire tube boilers; and in general is typical 70 of all boilers and their settings which usually include, in combination with the boiler, furnace walls forming a firebox and a combustion chamber.

As best illustrated in Fig. 2, the improved 75 bridge wall 9 separating the firebox from the combustion chamber, extends between the side walls 3 and 4 of the setting upward from the foundation 7 substantially to the fire line of the boiler.

The bridge wall 9 is provided with a relatively wide central notch 17 at its upper end directly beneath the boiler shell 18, and is further provided with a plurality of spaced 85 smoke breaking apertures 19 arranged in the bridge wall in rows upwardly from the upper level of the grate bars and around the notch 17.

The notch 17 preferably has a lower horizontal face 20 and parallel vertical side faces 21 and 22 merging with the upper peripheral faces 23 and 24 of the bridge wall.

Above the intersection of the notch side faces 21 and 22 with the bridge wall peripheral faces 23 and 24, the bridge wall is preferably imperforate, forming in effect side 90 curtain walls 25 and 26.

A superheater 27 is provided in the combustion chamber preferably immediately adjacent the apertures 19 in the bridge wall, steam from the boiler being delivered to the superheater through a suitable pipe line 28 in which, preferably adjacent the firing door 15 a suitable control valve 29 is located, and superheated steam from the superheater is delivered to the improved whirler nozzle 30 through a suitable pipe line 31 likewise provided preferably adjacent the valve 29 with a superheated steam control valve 32.

The upper pipe 33 of the superheater is 100 preferably provided with a plurality of spaced orifices 34 for delivering superheated steam therefrom into the combustion chamber 11 preferably immediately adjacent the bridge wall 9.

The whirler nozzle 30 is preferably directed 110 into the fire box 10 above the fuel bed 13 and is adapted for delivering whirling superheated steam into the fire box 10 of the furnace above the fuel bed.

The construction of the nozzle 30 by which the same delivers whirling superheated steam into the fire box is best illustrated in Fig. 4. The nozzle 30 includes connected upon the end of the pipe line 31, a cylinder 35 forming a steam chamber 36 which receives superheated steam from the pipe line 31, and the outer end 37 of which is closed by an orificed plug 38 having a plurality of angled 120 and intersecting passageways 39, 40, and 41 130

therein providing means for impinging a plurality of angled jets of superheated steam upon each other, whereby the variations in the velocity heads of the several impinging

5 jets set up a whirling motion in the several jets beyond their intersection, and a plurality of jets of whirling turbulent superheated steam is delivered into the fire box of the furnace from the steam chamber 36.

10 The intense heat generated in the firebox and combustion chamber, necessitates that the bridge wall 9 be made of very efficient refractory material, and a preferred construction for the bridge wall includes building up 15 the same of relatively large masses of plastic refractory clay, the apertures 19 being formed by laying ross-wise in the wall, lengths of pipe which if made of iron will burn out when the plastic wall is subject in position to 20 the action of the heat generated in the furnace, leaving the desired apertures in the refractory bridge wall.

25 The improved smoke consumer and fuel economizer thus described in detail is operated as follows:

30 A burning fuel bed 13 is provided in the firebox upon the grate in a usual manner, and the hot gases therefrom generate steam in the boiler 1, part of which steam is lead from the boiler through the pipe line 28 into the superheater 27 in the combustion chamber 11 immediately adjacent the apertures 19 in the bridge wall 9.

35 The superheater is heated by the hot gases passing through the apertures 19 in the bridge wall 9 and over the notch 17 therein, whereby superheated steam is formed in the superheater, part of which is delivered into the combustion chamber 11 through the plurality 40 of orifices 34 in the top pipe of the superheater, and the major portion of which is delivered to the pipe line 31 and to the whirler nozzle 30, the intersecting passageways 39, 40 and 41 of the nozzle imparting a rapidly 45 whirling motion to the superheated steam issuing from the nozzle, and delivers this whirling superheated steam from the nozzle 30 into the firebox 10 over the fuel bed.

50 This rapidly whirling superheated steam continuously impinges against the combustible gases and soot suspended therein which be rising from the fuel bed, and the whirling superheated steam simultaneously heats a substantial part of the gases and soot to their 55 combustion temperatures, and at the same time by the whirling motion intimately mixes the gases and soot with the necessary air to support combustion thereof.

59 This process is necessarily carried on at a relatively rapid rate, and in the event that complete combustion of the gases and soot has not taken place in the firebox, with the resulting formation of some smoke, this smoke is broken up as it passes through the apertures 65 19, in the bridge wall 9 and is again mixed

with air and brought to its combustion temperature by the superheated steam introduced in the combustion chamber through the orifices 34.

The combined action of the whirler nozzle 30 simultaneously heating to their combustion temperatures combustible gases and soot rising from the fuel bed, and mixing the same with quantities of air necessary for the combustion thereof, together with the breaking up of any smoke which may still be formed in the firebox by the action of the apertured bridge wall as the smoke passes through the same, and the final heating of the broken up smoke and air entering the combustion chamber by the superheated steam delivered into the combustion chamber by the superheater, provides for almost complete combustion of the available combustible material in the solid fuel in the fuel bed.

When properly operated by suitable manipulation of the valves 29 and 32, the device enables almost perfect combustion of solid fuel in the boiler furnace, with an eduction of smoke from the furnace chimney which is well within the limits prescribed by most smoke control laws.

In a single boiler installation the use of the aforesaid device saved 4½ tons of coal per week, as compared with the operation of the boiler without the present smoke consumer and fuel economizer.

I claim:

1. Combustion apparatus including a firebox, combustion chamber, and a bridge wall between the firebox and the combustion chamber, a plurality of apertures in the bridge wall, a superheater in the combustion chamber, a whirler nozzle directed into the firebox and in communication with the superheater, and an orifice in the superheater directed into the combustion chamber.

2. Combustion apparatus including a firebox, a combustion chamber, and a bridge wall between the firebox and the combustion chamber, a plurality of apertures in the bridge wall, a boiler operatively associated with the combustion chamber, a superheater in the combustion chamber communicating with the boiler, a whirler nozzle directed into the firebox and communicating with the superheater, and an orifice in the superheater directed into the combustion chamber.

3. In combination with the furnace of a boiler and the like, including a firebox, a bridge wall, and a combustion chamber, means including a nozzle having a plurality of intersecting passageways for delivering whirling superheated steam into the firebox, a plurality of apertures in the bridge wall, and means for delivering superheated steam into the combustion chamber.

4. Combustion apparatus including a firebox, a combustion chamber, and a bridge wall between the firebox and the combustion

chamber, means including a nozzle having a plurality of intersecting passageways for delivering whirling superheated steam into the firebox, a plurality of apertures in the bridge wall, and means for delivering superheated steam into the combustion chamber.

5. In combination with the furnace of a boiler and the like, including a firebox, a bridge wall, and a combustion chamber, means including a nozzle having a plurality of intersecting passageways for delivering whirling steam into the firebox, a plurality of apertures in the bridge wall, and means for delivering steam into the combustion chamber.

10. Combustion apparatus including a firebox, a combustion chamber, and a bridge wall between the firebox and the combustion chamber, means including a nozzle having a plurality of intersecting passageways for delivering whirling steam into the firebox, a plurality of apertures in the bridge wall, and means for delivering steam into the combustion chamber.

15. In combination with the furnace of a boiler and the like, including a firebox, a bridge wall, and a combustion chamber, means for intersecting a plurality of jets of superheated steam and delivering jets into the firebox after the intersection thereof, a plurality of apertures in the bridge wall, and means for delivering superheated steam into the combustion chamber adjacent the bridge wall.

20. Combustion apparatus including a firebox, a combustion chamber, and a bridge wall between the firebox and the combustion chamber, means for intersecting a plurality of jets of superheated steam and delivering jets into the firebox after the intersection thereof, a plurality of apertures in the bridge wall, and means for delivering superheated steam into the combustion chamber adjacent the bridge wall.

25. In combination with the furnace of a boiler and the like, including a firebox, a bridge wall, and a combustion chamber, means for intersecting a plurality of jets of superheated steam and delivering jets into the firebox after the intersection thereof, a plurality of apertures in the bridge wall, and means for delivering steam into the combustion chamber adjacent the bridge wall.

30. Combustion apparatus including a firebox, a combustion chamber, and a bridge wall between the firebox and the combustion chamber, means for intersecting a plurality of jets of superheated steam and delivering jets into the firebox after the intersection thereof, a plurality of apertures in the bridge wall, and means for delivering steam into the combustion chamber adjacent the bridge wall.

35. In combination with the furnace of a boiler and the like, including a firebox, a bridge wall, and a combustion chamber, means for intersecting a plurality of jets of superheated steam and delivering jets into the firebox after the intersection thereof, a plurality of apertures in the bridge wall, and means for delivering steam into the combustion chamber adjacent the bridge wall.

bridge wall, and a combustion chamber, means including a nozzle having a plurality of intersecting passageways for intersecting a plurality of jets of superheated steam and delivering jets into the firebox after the intersection thereof, a plurality of apertures in the bridge wall, and means for delivering superheated steam into the combustion chamber adjacent the bridge wall.

40. Combustion apparatus including a firebox, a combustion chamber, and a bridge wall between the firebox and the combustion chamber, means including a nozzle having a plurality of intersecting passageways for intersecting a plurality of jets of superheated steam and delivering jets into the firebox after the intersection thereof, a plurality of apertures in the bridge wall, and means for delivering superheated steam into the combustion chamber adjacent the bridge wall.

45. In combination with the furnace of a boiler and the like, including a firebox, a bridge wall, and a combustion chamber, means including a nozzle having a plurality of intersecting passageways for intersecting a plurality of jets of superheated steam and delivering jets into the firebox after the intersection thereof, a plurality of apertures in the bridge wall, and means for delivering steam into the combustion chamber adjacent the bridge wall.

50. Combustion apparatus including a firebox, a combustion chamber, and a bridge wall between the firebox and the combustion chamber, means including a nozzle having a plurality of intersecting passageways for intersecting a plurality of jets of superheated steam and delivering jets into the firebox after the intersection thereof, a plurality of apertures in the bridge wall, and means for delivering steam into the combustion chamber adjacent the bridge wall.

55. In testimony that I claim the above, I have hereunto subscribed my name.
